atty.

UNITED STATES PATENT OFFICE.

HERMAN ROEMER, OF CHICAGO, ILLINOIS.

WRINGER.

1,308,868.

Specification of Letters Patent.

Patented July 8, 1919.

Application filed March 3, 1917. Serial No. 152,414.

To all whom it may concern:

Be it known that I, HERMAN ROEMER, a citizen of the United States, residing at the city of Chicago, in the county of Cook and State of Illinois, have invented certain new and useful Improvements in Wringers, of which the following is a specification.

My invention relates to wringers which are used for removing the superfluous water from clothing and other materials. When such devices are power driven and large quantities of material are being passed rapidly therethrough they are liable to cause serious injury to the operator if any portion of the person or clothing is accidentally caught in the rolls. It is the object of my invention to provide means applicable, with slight changes or modifications, to such machinery as is commonly in use by which, in case of accident, imminent or actual, the free roll may be unseated and freed from its operative relation with the driving roll.

The principles of my invention are illustrated in the drawings, in which—

Fig. 1 is an elevation of a wringer equipped with my improvement;

Fig. 2 is an enlarged top view thereof;

Fig. 3 is a similar view partly in section of the upper part of such device showing my improvement;

Fig. 4 is an enlarged vertical section of the roller bearings and gearing of a typical wringer.

Further describing my invention with reference to the drawings: 1, 1 are the vertical standards of such machine. 2 is a lower cross bar and fabric guide. 3 is a driving shaft, journaled in bearing blocks 3', and 4 is the principal roller on such shaft. 5 is a roller mounted on shaft 6, journaled in bearing blocks 7. Said bearing blocks are slideable in the bearing guides 8, and shaft 6 is provided with gears 9 meshing with gears 10 on the main shaft 3. 11, 11 are gear housings. An arched evener 12 spans the space between the bearing blocks and the ends thereof rest on the slideable members, which play in the bearing guides. A bow-spring 15 is placed above the evener and a cross bar 16 bears centrally on the upwardly bowed portion of said spring.

The structures thus described are held in place by the upper cross bar or abutment piece 18, which is secured to the upper part of the standards 1, and through which pass the spacing screws 19, which bear in the

ends of cross bar 16, and by which the pressure of the rolls is regulated. The upper part of the frame is provided with a metallic framework which may consist of the 60 clips 20 secured to the upper ends of the standards 1, and connected by the transverse tie rods 21. A plurality of sliding bolts 24 and 25 are mounted on the upper face of the abutment piece 18, and the ends 65 thereof 24' and 25' are adapted to pass through openings 26 in the upwardly extended parts 27 of clips 20 which form striker plates to receive the ends of said bolts. Bolt 24 is secured in position by the 70 guiding strips 30. It is also provided with slots 31 and 32, the uses of which will be hereafter explained.

Bolt 25 has an arched portion 33. It is further provided with a tail piece 34 slideable in slot 31 of bolt 24 and under the guide 30. The outer portion is held in position by the guide 35, and it is further provided in the arched part thereof with opening 36. A plurality of plates 37 is secured 80 to the abutment piece 18, and between them on the pivot 40 is mounted a lever 41, which passes through slot 36 in bolt 25 and slot 32 in bolt 24 so that the bearings thereof in the two slots are substantially at equal 85 distances from the pivot 40. A spring 42 connects the lever 41 to a stationary lug 43, whereby the lever is normally held in the position shown in Fig. 1, so that the two bolts will be equally extended, and so that 90 the extremities thereof will pass into the openings in the striker plates 27 and be engaged therewith.

When the wringer is in use the relative parts will be in substantially the relation 95 shown in Figs. 1 and 2, the upper roller 5 being in contact with roller 4 under pressure of the bow spring 15, as established by the spacing screws 19. Said spring moreover acts to balance the pressure at the ends of 100 the rolls, thereby avoiding the necessity of special adjustment of the spacing screws. If any contingency arises on account of which it is necessary to free the rollers a quick pressure applied to the lever 41 will cause the 105 bolts 24 and 25 to be instantly withdrawn from the plates 27, whereupon the pressure of spring 15 will lift the weight of cross-bar 16 and abutment piece 18, and leave the roll 5 free to be unseated and the gears on its shaft 110 6 to be thrown out of mesh with the gears on shaft 3. The rolls thus become entirely in-

operative to exert any material pressure on anything which may have accidentally been drawn therebetween. The device may again be placed in operative condition by pressing 5 the handle to the lowest point, putting the abutment piece in its normal position, and releasing the lever, whereby the spring 42 will cause the bolts to engage the striker plates and cause said piece to be locked in 10 normal position.

I claim:

In a wringer; a frame, a plurality of rolls journaled therein, an abutment piece above the said rolls, a spring device interposed be- 15 tween the abutment piece and the rolls to hold the latter normally in coöperative re-

lation, striker plates on the said frame, a slotted bolt slidable on the abutment piece to engage one of said striker plates, a second bolt having an arched portion overlying the slotted portion of the first named bolt and provided with a slot, said second bolt being slidable on the abutment piece to engage the other of said striker plates, a plurality of plates on the sides of the abutment piece, and a lever pivoted between said plates to engage within the slots of said bolts. 20 25

In witness whereof, I have hereunto subscribed my name this 28th day of February, 30 1917, at Chicago, Cook county, Illinois.

HERMAN ROEMER.
